CLAIM

The ornamental design for a sound appreciation chair, as shown and described.

DESCRIPTION

FIG. 1 is a front, top, and right side perspective view of a sound appreciation chair showing the new design.

FIG. 2 is a rear, bottom, and left side perspective view thereof.

FIG. 3 is a front, bottom, and right side perspective view thereof.

FIG. 4 is a front elevational view thereof.

FIG. 5 is a rear elevational view thereof.

FIG. 6 is a top plan view thereof.

FIG. 7 is a bottom plan view thereof; and,

FIG. 8 is a left side elevational view thereof, the right side elevational view being a mirror image of the left side elevational view.

The broken lines depict portions of the sound appreciation chair that form no part of the claimed design.
